United States Patent Office.

DAVID ALTER, OF FREEPORT, PENNSYLVANIA, ASSIGNOR TO CHARLES W. BODEY, OF SAME PLACE.

Letters Patent No. 62,988, dated March 19, 1867.

IMPROVEMENT IN THE DISTILLATION OF BROMINE AND IODINE.

The Schedule referred to in these Letters Patent and making part of the same.

TO ALL WHOM IT MAY CONCERN:

Be it known that I, DAVID ALTER, of Freeport, in the county of Armstrong, and State of Pennsylvania, have invented a new and useful Improvement in Distillation of Bromine and Iodine; and I do hereby declare that the following is a full, clear, and exact description thereof, which will enable others skilled in the art to make and use the same, reference being had to the accompanying drawings, forming part of this specification, in which—

Figure 1 is a plan of my improved still.

Figure 2 is a sectional elevation of the same, also showing arrangement for distillation.

Figure 3 is an end elevation of the still.

Similar letters of reference indicate like parts.

The nature of this invention consists in the use of an alkali to absorb the fumes of bromine and hydro-bromic acid which would otherwise escape during the production and distillation of the above-named substances. For this purpose I have a stone still, A, made out of a solid block, the top of which is covered by a stone slab, A', well fitted and luted with a material included in a patent obtained by me. In the sides of the still holes are cut, through which the lead flue B, flanged at one end, is passed until the flange rests flush against the side; then on the other end a hub or shorter piece of pipe, C, flanged like the flue B, is slipped over the end of the flue B, and the seam closed by stamping or pounding against the ends. Against these flanges rests an iron ring, D, sharp on its edge, which is held in position and forced up, so as to make a tight joint, by means of two or more clamps, E, one end of each resting against the ring, while the other end bears on a block laid between it and the still. Through the middle of this clamp-bar E a bolt, F, passes, which goes through the side of the stone still A; the head of the bolt resting against the inside of the stone still, and the nut being on the outside of the clamp-bar E, will allow the whole to be tightened or slackened, as may be required, and thus will be enabled to insure a perfectly tight joint for the prevention of leakage of the contents of the still. Into the stone still A, fitted up as described, hot bittern is run, until only about four inches of space is left between the surface of the liquor and the stone cover A', covering the end of the funnel G, and thus forming a water or gas lute. Through this funnel G the acid and manganese employed are introduced, and heat applied by means of a movable furnace, which is run up to the still A and connected with the flue by a short pipe. Bromine and some hydro-bromic acid, with other gases and vapors, are liberated and forced through a lead pipe, H, surrounded with water; the end of this pipe H dips below the surface of some water contained in the glass jar I; the bromine condenses and falls in drops through this water, collecting on the bottom of the jar. Thus far there is no way provided for the escape of the uncondensed bromine vapors, gases, &c., other than by bubbling up through the water, which would entail a great loss of bromine from the heat imparted to the liquid by the passage of such a quantity of gases which still retain some heat, or by making an opening in some part of the pipe and allowing them to pass into the atmosphere and filling it with fumes of such an intolerable odor that no person could remain near the apparatus. To this condensing pipe H, and at a point just before it leaves the vessel J, containing the water for cooling, a pipe, K, is attached, and is made to pass up through the water, thus presenting the gases and vapors still further to the cooling influence of the surrounding water, and carrying any bromine which condenses back into the main pipe H, and will then pass into the jar I provided for its reception, while the gases flow through the pipe K, which bends downwards after it leaves the surface of the water and terminates below the surface of a solution of potassa, soda, or ammonia in the glass jar L—soda preferred for general use only on account of economy—when the bromine and hydro-bromic acid combine with the alkali, forming, in the case of potassa and soda, bromates and bromides, and in the case of ammonia, as long as in excess, a bromide only, all of which are fixed salts, and can be utilized either in that form, as obtained by crystallization from the liquid or by extraction by liberation with acid and condensation of the vapors in the form of bromine; and further, for the production of a bromide directly, I substitute a solution of whichever one of the alkalies which I desire to form a bromide for the water in the glass jar I, and allow the bromine to pass into the solution, whereby I obtain, in the case of potassa and soda, a mixed solution of a bromide and bromate; and in the case of ammonia in excess a bromide only. From this solution the bromide is separated

by crystallization. The whole constituting an apparatus so well adapted to the peculiar circumstances and actions which occur in this process as enables me, with a consumption of only one-fourth the amount of chemicals employed in the European process, to obtain the same quantity of bromine, and with much less labor.

What I claim as new, and desire to secure by Letters Patent, is—

The use of an alkali to absorb the fumes of bromine and hydro-bromic acid while in process of distillation, substantially as herein shown and described.

DAVID ALTER.
